PROCESS FOR PRODUCING KETENE

Crawford Hallock Greenewalt, Wilmington, Del.,
assignor, by mesne assignments, to Du Pont
Rayon Company, New York, N. Y., a corpora-
tion of Delaware

Application October 25, 1933, Serial No. 695,064

3 Claims. (CL 260—123)

This invention relates to an improved process for the manufacture of ketene and more particularly to a process for improving the yield of ketene as made by the pyrolysis of ketene-forming substances such as acetone.

The manufacture of ketene by pyrolysis of acetone is a well known process. An improved method of carrying out the pyrolysis at very high temperatures with very short times of contact is disclosed in the copending application of George D. Graves and C. H. Greenewalt, Serial No. 618,702, filed June 22/32. It has been found that subsequent losses of ketene may come about through the polymerization of the ketene as it is dissolved by unconverted acetone, condensed from the effluent gases. These losses may be substantial but may be avoided by the process of the present invention.

This invention has as an object the production of ketene in high yields by the pyrolysis of acetone. A further object is the recovery, without loss of ketene, of unconverted acetone from the pyrolysis products so that it can be returned to the pyrolysis tube for re-use.

These objects are accomplished by the following invention wherein the pyrolysis vapors containing ketene and the ketene-forming substance such as acetone are first passed through a pre-cooler or heat-exchanger in which the pyrolysis vapors are brought approximately to their dew-point, and, second through a condensing means arranged so that the condensed ketene-forming substance flows downward into the warm zone counter-current to the incoming vapors. The ketene-forming substance is thus condensed and the ketene removed as a vapor, the loss of ketene by solution in the ketene-forming substance and subsequent polymerization being avoided.

Various substances may be pyrolyzed to yield ketene. Acetic acid, acetic anhydride, acetaldehyde, and acetone may be thus employed. The preferred substance is, however, acetone. This is pyrolyzed by any of the methods known in the art including that of the copending Graves and Greenewalt application above described.

The pyrolysis vapors issuing from the high temperature zone are cooled to approximately their dew-point in any desired manner. The vapors at their dewpoint are then admitted to a reflux condenser capable of returning the major portion of the unconverted acetone as a liquid to a receiver below the condenser. The reflux condenser is a very essential feature since by this means the returning liquid is stripped of ketene by the incoming warm vapors. The condensed

acetone in the receiving vessel is either drawn off or held at about 56° C. in order to discharge any residual dissolved ketene and to prevent the solution of any appreciable amount of ketene from the vapor space. The acetone which is 5 essentially at its boiling point may be allowed to run continuously from this receiver to a distilling column, from the top of which may be taken recovered acetone suitable for reaction in the process, and from the bottom of which may be recovered any small amounts of acetic acid or acetic anhydride which may result from water in the original acetone or from side reactions. The material thus condensed contains a negligible amount of ketene polymer. The uncondensed 15 gases issuing from the top of the reflux condenser will contain all of the original ketene and may be treated in any desired manner.

The invention, therefore, comprises the following steps.

I. The pyrolysis vapors containing ketene are cooled to approximately their dew-point. By dew-point is meant that temperature at which the first drop of condensate forms.

II. The vapors at their dew-point are admitted 25 to the bottom of a reflux condenser which returns the major portion of the unconverted acetone as liquid to a receiver below the condenser and passes substantially all of the ketene to suitable absorption apparatus designed for its utilization.

The reflux condensation of the acetone is the most important and really essential step in carrying out the present invention since the liquid being returned down the condensing surface continuously meets ascending warm vapors which strip out ketene and permits it to remain in solution for only a very small increment of time. The liquid leaving the bottom of the reflux condenser is thus rendered substantially free of dissolved ketene, and the major portion of the ketene 40 passes from the top of the condenser. This arrangement effects in essence a vapor phase separation of acetone from ketene, in which phase there is substantially no polymerization of ketene.

The maintenance of the acetone in the receiver 45 under the condenser at or near the boiling point of the acetone in order to prevent condensation of acetone prior to the entrance of the pyrolysis vapors into the reflux is a desirable refinement in the process since by the use of this step there is substantially no loss of ketene through solution in the recovered acetone and subsequent polymerization.

The recovered acetone at or near its boiling point may be run from the receiver continuously 55

or discontinuously to a rectification column which separates pure recovered acetone from any high boiling constituents which may be present. These high boiling constituents are substantially free from ketene polymers and are negligible in quantity compared to the ketene produced.

The following example is given in illustration of the process of the present invention but is by no means to be regarded as limitative. The numbers used in designating the apparatus refer to the corresponding numbers in the accompanying drawing.

Acetone from tank (1) for fresh acetone or tank (2) for recovered acetone is pumped by pump (3) at the rate of 75 cc. per minute through a $\frac{1}{4}$ inch inside diameter copper tube (4), so placed in an electric furnace that 90 inches of the tubing lie within a zone between 760 and 810° C. The vapors issuing from the furnace are conducted through a coil (5) of $\frac{3}{8}$ " copper tubing 15 feet long, held in a water bath maintained at a temperature which will cool the vapors to their dew-point or about 54° C. (Theoretically, the dew-point ranges from a temperature near the boiling point of ketene with 100% conversion to the boiling point of acetone with 0% conversion. Actually, it is within a few degrees of the latter because the per cent conversion is usually small). The cooled vapors are admitted to a cylindrical copper vessel (7), 4 inches in diameter and 9 inches high, surmounted by a water-jacketed reflux condenser (6) 10 feet high and 1 inch in diameter. Vessel (7) is connected to the recovered acetone tank by a vent line (14). The condensed acetone, which is returned by the reflux condenser to the cylindrical receiver beneath it, is held therein at about 56° by the application of heat to the receiver. The condensed acetone, essentially free from dissolved ketene, and substantially at its boiling point, is withdrawn continuously from an outlet located 5 inches above the bottom of the re-boiler vessel, and allowed to flow to a rectifying column (11), from the top of which acetone, substantially free from impurities, is withdrawn through a condenser (12) for recirculation. A small still pot (13), beneath the rectification column served to collect high boiling constituents which may be drawn off through pipe (20). It is kept substantially free from acetone by the application of heat.

The ketene, together with gases resulting from the decomposition of ketene, and also a small amount of uncondensed acetone, passes from the top of the reflux condenser through pipe (18) to the bottom of an absorption column (8), down which water is pumped from tank (9) through pump (16) at a rate sufficient to absorb the ketene and convert it to acetic acid which flows continuously from the bottom of the absorption column and is stored in reservoir (17). Uncondensed vapors are passed through absorbers (15) and vented through pipe (16). Absorbers (15) are not essential.

The apparatus was operated as described for 65 154 minutes. It was then found that the liquor produced in the absorption tower contained acetic acid equivalent to 21.7 mols of ketene. The residue withdrawn from the still beneath the acetone rectification column was found to contain a small amount of acetic anhydride, together with some acetone, but essentially no ketene polymer. By deducting the amount of acetone recovered by distillation of the liquid products from the amount fed to the pyrolysis 70 tube, it was found that 26.4 mols of acetone had

been consumed. Since 23.26 mols of acetic acid were produced (21.7 as acetic acid, 1.56 as acetic anhydride as above indicated) the yield was 88.2%. The loss may be accounted for as gaseous decomposition products of ketene. 5

The transformation of the ketene to acetic acid is merely one method of utilizing the ketene and is here adopted largely because it furnishes an easy method of determining the yield. The ketene may also be reacted with acetic acid, 10 aniline, alcohols and the like.

The improved method for preventing loss of ketone can be applied to any mixture of vapors obtained by pyrolysis of acetone, acetaldehyde, acetic acid, acetic anhydride, or other ketene 15 forming substances. The pyrolysis may be any of those disclosed in the prior art although the pyrolysis process of the above identified Graves and Greenewalt application gives improved yields.

Any desired means may be used for precooling the pyrolysis product issuing from the reaction tube, from the high temperature of decomposition to the dew-point of the pyrolysis vapors. Water-cooled coils or any type of heat-exchanger may be used, or a part of the cooling 20 may be brought about by spraying an inert liquid such as acetone into the gas stream. There should be little or no actual condensation of acetone in this part of the process.

Any efficiently operating reflux condenser will 30 serve to separate the ketene from unchanged acetone without appreciable loss of ketene dissolved in the liquid condensate. A reflux condenser is particularly well adapted to this purpose because the liquid condensate is continuously stripped of ketene by the hot ascending vapors. 35

Through the use of this invention loss of ketene by polymerization to ketene dimer may be almost entirely eliminated. This loss has 40 never been avoided in the prior art except in processes wherein the ketene is utilized practically immediately after formation, no condensation of acetone being permitted until the ketene has reacted. 45

This latter exception requires a fractionation of large amounts of unchanged acetone from the reaction product as a separate step in the process, a step which is obviously disadvantageous. In the process of the present invention the acetone recovery is continuous. This continuous recovery minimizes the amount of acetone in process and permits the use of inexpensive recovery equipment. There is an additional important advantage in the economy of heat since 50 the acetone is fed to the rectification column essentially at its boiling point. 55

As many apparently widely different embodiments of this invention may be made without departing from the spirit and scope thereof, it 60 is to be understood that I do not limit myself to the specific embodiments thereof except as defined in the appended claims.

I claim:

1. In a process for the preparation of ketene 65 by the pyrolysis of a ketene-forming substance, the step which comprises leading the pyrolysis gases thru cooling means to reduce their temperature to the dew point, then upward thru a reflux condenser whereby to effect substantially vapor phase separation of ketene from the ketene-forming substance, the condensed ketene-forming substance being maintained at substantially its boiling point. 70
2. In a process for the preparation of ketene 75

by the pyrolysis of acetone, the step which comprises passing pyrolysis gases cooled substantially to their dew point thru a reflux condenser counter-current to a descending flow of condensed acetone whereby to effect substantially vapor phase separation of the acetone from the ketene, the condensed acetone being maintained substantially at its boiling point to prevent absorption of ketene therein.

10 3. In the process of producing ketene by the

pyrolysis of acetone, the step which comprises leading the pyrolysis gases thru cooling means to reduce their temperature substantially to the dew point, then upward thru a reflux condenser whereby to effect substantially vapor phase separation of acetone from ketene, the condensed acetone being maintained at substantially its boiling point.
